UNITED STATES PATENT OFFICE.

ISAAC V. HODGIN, OF GREENE, IOWA.

HEATER FOR STOCK-WATERING TANKS.

1,372,815.

Specification of Letters Patent. Patented Mar. 29, 1921.

Application filed October 9, 1919. Serial No. 329,443.

To all whom it may concern:

Be it known that I, ISAAC V. HODGIN, a citizen of the United States, residing at Greene, in the county of Butler, State of Iowa, have invented certain new and useful Improvements in Heaters for Stock-Watering Tanks; and I do hereby declare the following to be a full, clear, and exact description of the invention, such as will enable others skilled in the art to which it appertains to make and use the same.

This invention relates to heaters for stock tanks, although it will of course be understood that it may be employed for heating liquids in various types of containers and for any of the various purposes for which it may be adapted.

The object of the invention is to provide a construction of heater that will insure an efficient circulation of heated water through the tank so that the entire body of water will have a substantially uniform temperature, the result to be attained with economy of fuel.

A further object of the invention is to provide a construction in which the major heating effect will be had through the medium of water taken into the heater and discharged from it into the tank, the particular construction and arrangement being such that the body of cooler water in the tank, will not interfere by its cooling effect, with the circulation of water through the heater. Other objects and advantages of the invention will be understood from the following description.

In the drawings:

Figure 1 is a view showing a tank equipped with the present heater, the tank being shown in vertical section with its central portion broken away to permit of showing on a larger scale and the heater being shown in elevation at its water intake side.

Fig. 2 is a top view of the heater, a part of its intake water pipe being broken away.

Fig. 3 is a transverse section on line 3—3 of Fig. 2, through the burner, the water inlet and outlet and the associated parts.

Fig. 4 is a vertical section on line 4—4 of Fig. 2, illustrating the water inlet opening through the hot plate.

Referring now to the drawings the present heater comprises a hollow casing, preferably of sheet metal and including a base 10, from one end of which extends the vertical flue 11, that is preferably rectangular in

cross section, although it may have other different shape, the length of this flue being such that its upper end will stand well above the water level of the tank. The flue 11 is 60 provided with a removable cover 12 and near its upper edge are formed in its side walls, the air inlet openings 13.

At the end of the base opposite to the flue 11 and rising from the top of the base, is an 65 air circulating pipe or stack 14 so that air may circulate down through the flue 11, thence transversely through the base and finally upwardly and out of the top of the stack.

A part of the top wall of the base is formed by a comparatively heavy iron plate 15 that constitutes what might be termed a "hot plate" for the heater, it being disposed directly over a burner 16, preferably of the 75 hydro-carbon type, that is disposed in the base and directly beneath the plate. Fuel for the burner is supplied through a pipe 17, of the hollow wire type, and leads upwardly through the flue 11 and outwardly through 80 its wall near to its upper end, where it may connect with any source of supply.

Over the hot plate 15 and extending downwardly of one side of the base of the apparatus, is a plate 18, having marginal 85 flanges that are secured to the base and which hold the plate in spaced relation to the side of the base and to the hot plate. The portion of the plate 18 that depends at the side of the base is provided with an inlet pipe 19 90 for connection of a hose or other type of pipe 20 that leads to the opposite end of the tank 21 from that end in which the heater is disposed. The interspace between the plate 18 and the side wall of the base and the hot 95 plate, constitutes a water circulating chamber, the side edge portion of the hot plate that overhangs the side wall of the base and within the said chamber, having a series of vertical openings 21 through it to permit of 100 passage of water from the vertical part 22 of the water chamber to the horizontal part 23, from which latter the water passes through a series of perforations 24 in its opposite side, to the body of water in the 105 tank.

In order that the water passing over the hot plate 15 may not be materially cooled by the body of water in the tank and circulation of water through the heater be retarded, a plate 25 is provided above the horizontally extending portion of the plate

18 and has depending marginal flanges 26 that are united to the corresponding portion of the plate 18 to hold the plate 25 in spaced relation thereto so that there is provided a 5 dead air space 25' that constitutes an insulating medium that prevents radiation of heat units from the water through the top portion of the plate 18, as will be understood.

10 To vary the draft to the burner, the adjacent wall of the flue 11 has disposed against it a slide plate 27, having suitable guides and which when shifted vertically varies the effective opening between the flue 11 and the portion of the base occupied by the burner, the lower edge portion of the plate 27 having an opening 28 through it to prevent entire shutting off of the draft.

It will thus be seen that there is provided 20 a construction in which water will be drawn from one end of the tank and passed through the heater and then will discharge into the body of water at the other end of

the tank at an increased temperature. Thus will be established a circulation in the tank 25 from end to end that will be modified by the natural movement of heated water upwardly through a body of water of lesser temperature.

What is claimed is:

30 A water heater comprising a hollow base having an inlet flue and a stack, a burner within the base, a hot plate disposed to be heated by the burner, a water passage extending vertically of one side of the base 35 and over the hot plate and for which the hot plate constitutes a bottom, and an air chamber covering the portion of the passage that traverses the hot plate, the passage having an inlet and an outlet.

40 In testimony whereof, I affix my signature, in the presence of two witnesses.

ISAAC V. HODGIN.
